Frank Warren

UNITED STATES PATENT OFFICE.

LARS SALVESEN, OF SATSUP, WASHINGTON.

SAW-SUPPORTING DEVICE.

1,331,279.

Specification of Letters Patent. Patented Feb. 17, 1920.

Application filed July 15, 1919. Serial No. 311,076.

To all whom it may concern:

Be it known that I, LARS SALVESEN, a subject of the King of Norway, residing at Satsup, in the county of Yakima and State 5 of Washington, have invented a certain new and useful Improvement in Saw-Supporting Devices, of which the following is a specification.

My invention relates to improvements in 10 devices for supporting saws that are adapted to be used for undercutting timber, as for sawing a fallen log and the object of my invention is to provide a saw support that is simple, compact and durable in construction, efficient in operation and that is susceptible of a wide range of adjustment.

The invention consists in the novel construction, adaptation and combination of 20 parts of a saw supporting device as will be more clearly hereinafter described and claimed.

I accomplish these objects by devices illustrated in the accompanying drawings, wherein—

25 Figure 1 is a view in elevation on a reduced scale showing my saw supporting device as it may appear when in use on a log, the log being shown partly in cross-section;

Fig. 2 is a plan view of my invention;

30 Fig. 3 is a view in cross-section substantially on broken line 3, 3 of Fig. 2, certain parts being broken away; and

Fig. 4 is a fragmentary view in elevation showing parts of the saw supporting arm 35 and toothed retaining member that is associated therewith.

Referring to the drawings, throughout 40 which like reference numerals indicate like parts, the numeral 5 designates a shank that is flattened to a chisel edge at its forward end as at 6 and is bifurcated to form two rearwardly projecting members 7 and 8, the member 7 being longer than the member 8 and having a square end 10 that is adapted 45 to receive the blows of a sledge or hammer by which the flattened end 6 of the shank may be driven into a log as shown in Fig. 1.

Operatively disposed between the two shank members 7 and 8 is an arm 12 that is 50 provided with a longitudinally extending slot 13 and has its outer end bent at right angles to the body thereof to form a cir-

cular block 14 into which may be screwed a stud pin 15 that forms a bearing for a roller 16, which roller is provided with a plurality 55 of peripheral grooves 17 in which the back of a saw 18 may operate.

20 is a rectangular plate that is provided on one side with radial teeth 21 and on the other side with two lugs 22 and 23 that are 60 disposed on the opposite sides of a perforation 24, as shown in Fig. 4, and are arranged to project into the slot 13 so that the arm 12 may be moved lengthwise without moving the plate 20 but can not be turned on a pivot 65 unless the plate is turned.

25 is a rectangular plate, of substantially the same dimensions as the plate 20, that is provided with angular or beveled edges 26 and is adapted to be inserted within a suitable recess in the inner wall of the shank member 7 so that the plate is flush with the inner wall of the shank member.

The plate 25 is provided with a centrally disposed perforation 27 and is further provided around such perforation with radially arranged teeth 28 that effect a locking engagement with the teeth 21 on the plate 20.

The shank members 7 and 8 are perforated so that a bolt 30 may be passed transversely 75 therethrough and through the plates 20 and 25, the square head of the bolt being arranged to fit within a suitable recess 31 in the outer side of the shank member 8 whereby the bolt is prevented from turning.

The threaded end of the bolt 30 is arranged to screw within a nut member 32 that is provided at its outer end with a cross-pin 33 by which the nut may be turned, a washer 34 preferably being interposed between the 80 nut 32 and the side of the shank member 7.

When the nut 32 is screwed tightly against the washer 34 the arm 12 will be rigidly clamped in a fixed position and when the nut 32 is loosened the shank members 7 and 8 will easily spring apart far enough to permit the arm 12 to be freely moved lengthwise and to permit the teeth on the plate 20 to ride over the teeth on the member 25 as such arm is turned about the pivot bolt 30.

100 The arm 12 may be turned throughout the greater part of one complete revolution and may be moved lengthwise as far as permitted by the slot 13 thus making it possible

to adjust the saw supporting roller both vertically and horizontally in order to support the saw in the most efficient manner.

Obviously changes may be made in the 5 precise form of construction and arrangement of parts of my invention without departing from the spirit thereof.

What I claim is:

1. A saw supporting device comprising a 10 bifurcated shank having one end that is flattened and arranged to be driven into a piece of timber, an arm having a longitudinal slot, means engageable within said slot for releasably securing said arm between the 15 bifurcated portions of said shank in adjusted positions, and a grooved saw supporting roller journaled on the outer end of said arm.

2. A saw supporting device comprising a 20 shank having a bifurcated body portion and a flattened end that may be driven into a piece of timber, an arm having a longitudinally arranged slot, a toothed member movable lengthwise of said arm but secured 25 against rotation with respect thereto, a rigid toothed section on the inner side of one of the bifurcated portions of said shank and arranged to engage with said toothed member that is movable within the slot in said 30 arm, a bolt extending crosswise through said shank, said arm and said toothed members, a nut arranged to screw on to said bolt to

clamp said arm in various adjusted positions; and a saw supporting roller journaled on the outer end of said arm. 35

3. A saw supporting device comprising a shank having a bifurcated body and a flattened end that may be driven into a piece of timber, the outer side of one of said bifurcated body portions being recessed for the 40 reception of a bolt head and the inner side of the other of said bifurcated body portions being recessed at a point substantially opposite the recess for said bolt head, a longitudinally slotted arm interposed between the 45 two sides of said bifurcated shank body, a toothed plate removably disposed within the recess in the inner surface of one of said bifurcated body portions, a toothed member arranged to interfit said toothed plate and 50 provided with lugs that project into the slot in said arm to prevent said toothed member from turning relative to said arm, a bolt extending through said shank, said toothed member and said toothed plate, a nut on 55 said bolt, a cross-pin for turning said nut, and a saw supporting roller arranged with its axis at right angles to the longitudinal axis of said arm and rotatably mounted on the outer end of said arm. 60

In witness whereof I hereunto subscribe my name this 7th day of July, A. D. 1919.

LARS SALVESEN.
